COMBINED GOLF, BASEBALL AND BASKETBALL GAME TARGET

Joseph D. Benigno, 13 Barry Park Court,
Searington, N.Y. 11507

Filed Mar. 4, 1968, Ser. No. 10,821

Term of patent 14 years

Int. Cl. D21—1

U.S. Cl. D34—5

FIG. 1 is a perspective view of the combined golf, baseball, and basketball game target showing my new design;

FIG. 2 is a front view;

FIG. 3 is a side view, the opposite side of the combined golf, baseball and basketball game target being substantially plain and the rear thereof being substantially plain.

The broken line showing of game balls is for illustrative purposes only.

I claim:

The ornamental design for a combined golf, baseball and basketball game target, substantially as shown and described.
